Primary Examiner — Mark Goodwin(74) *Attorney, Agent, or Firm* — Brian J. Teague**(57) CLAIM**

I claim the ornamental design for a device for supporting an object, as shown and described.

DESCRIPTION

FIG. 1 is a perspective view of a device for supporting an object showing my new design;

FIG. 2 is a front elevational view thereof;

FIG. 3 is a rear elevational view thereof;

FIG. 4 is a top view thereof;

FIG. 5 is a right side elevational view thereof;

FIG. 6 is a left side elevational view thereof; and,

FIG. 7 is a bottom view thereof.

Specific features shown in broken lines do not form any part of or otherwise limit the claimed design.
